UNITED STATES PATENT OFFICE.

JOHN M. HANSEN, OF PITTSBURG, PENNSYLVANIA, ASSIGNOR TO FORGED STEEL WHEEL COMPANY, OF PITTSBURG, PENNSYLVANIA, A CORPORATION OF PENNSYLVANIA.

APPARATUS FOR FORGING WHEELS.

No. 866,024.

Specification of Letters Patent.

Patented Sept. 17, 1907.

Application filed May 19, 1906. Serial No. 317,737.

To all whom it may concern:

Be it known that I, JOHN M. HANSEN, a resident of Pittsburgh, in the county of Allegheny and State of Pennsylvania, have invented a new and useful Improvement in Apparatus for Forging Wheels; and I do hereby declare the following to be a full, clear, and exact description thereof.

My invention relates to apparatus for forging steel car wheels and the like, and its object is to provide an apparatus of this character by which the wheels are formed by purely upsetting or compressing action and without the production of scrap or waste. It involves apparatus suitable for the practice of the methods described in applications filed by me of even date herewith, Serial Nos. 317,733, 317,736, and 317,738.

The invention comprises, generally stated, a combination of three sets of male and female dies by which a bowl-shaped or concavo-convex blank is first produced, the web portion is thinned and brought to proper form, the hub is developed by an upsetting operation and the tread or flange is compressed and brought to finished shape, said sets of dies decreasing successively in height and increasing in width, as hereafter described.

In the accompanying drawings Figures 1, 2 and 3 are vertical sections partly in full lines showing in one form the first set of dies included in the invention in their several positions in operating upon the blank; Fig. 4 is a top view of the bottom or female die of said 30 Figs. 1-3; Figs. 5 and 6 are vertical sections partly in full lines of the second set of dies; and Figs. 7 and 8 are like views illustrating the third set of dies.

Any suitable dies embodying the general principles hereafter described may be employed for the first forging operation, such for example as the dies illustrated in the said method applications Serial Nos. 317,733 and 317,736.

The dies herein illustrated are those more specifically adapted for the practice of the method set forth in said 40 application Serial No. 317,736.

The three sets of dies, *viz.*, those shown in Figs. 1 to 4 operating in combination with the other sets shown in Figs. 5 and 6, and those shown in Figs. 7 and 8, are adapted to be used in succession, and completely transform the blank into a finished car wheel. The first set of dies as illustrated in Figs. 1 to 4, is composed of the bottom female die 1 and a co-operating top or male die 2. The cavity 3 of the bottom die is preferably bowl-shaped, having the vertical walls 4; the 45 curved web forming floor portion 5 and the central opening 6 through which the piercing mandrel 7 is adapted to be forced in the forming of the blank. The upper male die 2 has the annular curved projection 8 and the central hub forming cavity 9. These

dies operate to bring the blank into bowl-shape and 55 form a rudimentary hub. To that end the blank 10, brought to a proper forging heat is placed upon the die 1, as shown in Fig. 1, and as the top forging die 2 descends it forces the blank down into the die cavity 3, the position of the blank before the upper dies reach 60 their lower position being illustrated in Fig. 2, and the final position of the blank being illustrated in Fig. 3. In this way it will be seen that the rim portion 11 of the blank is turned upwardly while the web forming portion 12 thereof is substantially thinned and the 65 metal forced centrally in order to aid in forming the hub. Either during this forging operation, that is, during the descent of the upper die, or after the descent of the same, the piercing mandrel 7 is moved longitudinally, such as by raising the same so as to pierce 70 the blank and carry the central portion thereof longitudinally of the axis of the blank, so forming a rudimentary hub 13 which is illustrated as turned upwardly within the hub forming cavity 9 of the upper die. The final position of the piercing mandrel is 75 shown in Fig. 3, and, in case that mandrel is not forced upwardly until after the completion of the stroke of the upper die 2 Fig. 3 also illustrates the position of the dies, the mandrel and the blank. By this set of dies I thus produce a concavo-convex, or substantially bowl-shaped blank with the hub portion 80 developed in rudimentary form.

In the dies shown in Figs. 5 and 6 the rim of this blank is upset so as to develop the tread and flange of the wheel and at the same time the rudimentary hub 85 portion is also upset, so forming the tread and its flange 14, and completing the hub portion 15. It will be seen that these dies are constructed practically as follows: The lower die 16 has the central hub cavity 17 and the inclined web forming or supporting face 18 90 and beyond the same the annular flange forging recess 19 connected with the web forming face by the annular curved shoulder 20. Within this die is mounted the mandrel 21 illustrated as operated by a ram 22. The upper die 23 has the annular tread forming cavity 24 95 and within the same the annular curved projection 25 fitting within the cavity of the blank, and within that the central hub forming cavity 26 above which is the central opening 27 into which the mandrel 21 passes during the forging operation. The annular tread forging cavity 24 has the outwardly inclined face 28 and beyond the same the flaring flange forging face which 100 co-operates with the annular recess 19 of the lower die in forging the flange portion of the tread. The blank 30 formed in the dies 1 to 3 is preferably re-heated and 105 placed upon the lower die 16, the mandrel 21 raised through the same and the upper die 23 forced downwardly for the forging stroke. In this stroke it upsets

the rudimentary hub developed in the dies 1 to 3, upsetting it and bringing it to the finished form within the die cavities 17 and 26, and centering the hub with reference to the web portion of the wheel. At the same time, in case the web portion 12 has not been brought to finished thickness, it is forged between the web face 18 and the annular projection 25, being by these faces brought to finished thickness and the surplus metal forced inwardly to aid in forming the hub.

10 By the same stroke the upper die upsets the rim forming portion 11 of the blank and swages it so as to form the tread 14 of the finished wheel, in this action first forcing the metal inwardly and then forcing the surplus metal outwardly into the flange forming cavities 19 and 29 and forming the flange 31 of the tread.

The finished wheel is produced from this blank by the action of the dies shown in Figs. 7 and 8, it being preferred that these dies operate upon the blank when at a lower temperature so that the blank can be transferred to these dies as shown in Fig. 7. This third set of dies is provided with substantially similar cavities to the second set of dies, the similar parts being marked with the same reference numerals accompanied by the exponent *a*. In this set of dies the web is given the desired reverse curve and the tread and flange portions while at a low heat are subjected to heavy compression to further work the metal thereof and produce the desired fiber structure to give high strength and wearing qualities.

30 It will be noticed that the three sets of dies above described are of substantially similar form, that is, of concavo-convex form, the dies increasing in width and decreasing in depth successively, the first set of dies having a deep projection so as to raise the outer rim portion thereof to considerable height, while in the next set of dies this rim portion is spread out wider and upset and centered with relation to the web, and in the final set of dies the blank is spread out still wider and brought to completed form, the three sets of dies thus coöperating by somewhat similar forms of die projections and cavities so that by the three forging strokes of these dies a complete finished wheel is produced from a flat blank.

What I claim is:

45 1. In apparatus for forging car wheels, the combination of three sets of dies, each set having a hub cavity, an annular rim cavity, and an annular web reducing portion,

nular rim cavity, and an annular web reducing portion, the rim cavity of the first set being deeper and narrower than the other sets.

2. In apparatus for forging car wheels, the combination 50 of three sets of dies, one die of each set having an annular web reducing projection, said projections decreasing in height and increasing in width in the several sets.

3. In apparatus for forging car wheels, the combination 55 of three sets of dies, each set of dies having a hub cavity, a rim cavity, and an annular web forming portion, the hub cavity of the first set being deeper and narrower than the other sets and the web forming projections decreasing in height and increasing in width in the several sets.

4. In apparatus for forging car wheels, the combination 60 of three sets of dies, each set having a hub cavity and a rim cavity; and an annular web forming portion, the hub cavity in the first set being formed mostly in one of said dies and that of the succeeding set being substantially equal in both of the dies.

5. Apparatus for forging car wheels, comprising a set of dies having a hub cavity, an annular rim cavity, and an annular web reducing portion, the hub cavity being mostly in one die, and an eye-forming piercing mandrel arranged to be projected through an opening in the other die thereby forcing the displaced metal into the larger hub cavity of the first die.

6. In apparatus for forging car wheels, comprising a pair of dies, one of which is provided with a bowl-shaped cavity having substantially vertical walls, the other die 75 being provided with an annular web forming projection, said dies having a rim cavity which is narrow diametrically and deep axially of the dies, and a web reducing cavity which is narrower than the rim cavity.

7. Wheel forming apparatus comprising a pair of dies, one of which is provided with a bowl-shaped cavity having substantially vertical walls and having a central opening therein, and the other die being provided with a central hub cavity and a deep annular web forming projection surrounding the same, and a separately operated piercing 85 mandrel arranged to be projected through the opening in the first named die.

8. In apparatus for forging car wheels, the combination 90 of three sets of dies, each set having a hub cavity, an annular rim cavity and an annular web reducing portion, the rim cavity of the first set being deeper and narrower than the other sets and the web forming projections decreasing in height and increasing in width in the several sets, each set of dies being provided with a central opening, an eye piercing punch working through the opening of the first set, and a mandrel working through the opening of each succeeding set.

In testimony whereof, I the said JOHN M. HANSEN have hereunto set my hand.

JOHN M. HANSEN.
